[57] CLAIM

The ornamental design for a bottle, as shown and described.

DESCRIPTION

FIG. 1 is a top perspective view of a bottle showing our new design;

FIG. 2 is a top plan view thereof;

FIG. 3 is a front elevation view thereof;

FIG. 4 is a rear elevation view thereof;

FIG. 5 is a bottom plan view thereof; and,

FIG. 6 is a top perspective view of a second embodiment of FIG. 1, the difference residing in the addition of an ornamental blow hole.
